UNITED STATES PATENT OFFICE.

JOHANN G. PETERSON, OF JERSEY CITY, NEW JERSEY, ASSIGNOR TO MANHATTAN ELECTRICAL SUPPLY COMPANY, OF JERSEY CITY, NEW JERSEY, A CORPORATION OF NEW JERSEY.

SEPARABLE ATTACHMENT-PLUG.

1,093,468.

Specification of Letters Patent. Patented Apr. 14, 1914.

Application filed March 31, 1913. Serial No. 758,013.

To all whom it may concern:

Be it known that I, JOHANN G. PETERSON, a citizen of the United States, residing at Jersey City, in the county of Hudson and State of New Jersey, have invented certain new and useful Improvements in Separable Attachment-Plugs, of which the following is a specification.

This invention relates to separable attachment plugs, among the principal objects of the invention being the provision of an article of this character which is simple in construction, which can be readily and inexpensively made and wherein the parts of the body are rigidly and substantially held in proper position.

In the drawings accompanying and forming part of the present specification, I have shown in detail one of the several conventional forms of embodiment of the invention, which to enable those skilled in the art to practise the same will be set forth fully in the following description. I do not restrict myself to this disclosure; I may depart therefrom in several respects within the scope of the invention defined by the claim following said description.

Referring to said drawings: Figure 1 is a vertical sectional view of the body of a separable attachment plug, involving my invention. Fig. 2 is an elevation of the removable or cap member of the device. Fig. 3 is a vertical section on the line 3—3 of Fig. 1. Fig. 4 is a top plan view of the plug, and, Fig. 5 is a perspective view of a spring finger.

Like characters refer to like parts throughout the several figures.

The plug comprises in its make-up a body as 2 and a separable member or cap as 3. The body in turn consists of a base such as that denoted in a general way by 4, and a contact shell 5, the base 4, as illustrated comprising the main section 6 and the auxiliary section 7 both of insulating material such for example as porcelain or any of the compositions now employed in the manufacture of attachment plugs. The two sections 6 and 7 are connected together in any desirable manner, the screw 8 being shown for this purpose, and extending through registering bores in the two sections 6 and 7 and having a threaded connection with the wall of the bore in the section 7. The head of the screw fits against the bottom of a counterbore 9 in which said head is situated and which leads

from the aperture 10 in the top of the section 6. The contact shell 5 surrounds the section 4 and its outer edge bears against a circumferential shoulder 11 on said section 6, which is conveniently formed by peripherally reducing said section 6. The contact shell 5 has at its lower end the flange or bottom 12 clamped between the sections 6 and 7 and slotted, however, to provide for the passage of the upward projecting portions of the section 7. Said flange 12 fits a rabbet or groove 12 in the section 7 to thus aid in holding said contact shell in place.

As will be understood the shell 5 constitutes a lateral contact for coöperation with a contact in a socket. The end contact of the plug is designated by 13 being located approximately centrally of the lower end of the base 4 and having a substantially central opening threaded for engagement with the threads of the connecting screw 8. The central or end contact or disk 13 has an approximately L-shaped extension 14 disposed in a notch 15 in said section 7, the outer branch of said extension 14 resting against the top of said notch or slot 15. Owing to the fact that said extension fits comparatively closely in said slot lateral motion of said extension is prevented, and it also follows that rotation of the central contact or disk 13 cannot occur.

There are two spring fingers as 16 and 17 situated in longitudinally extending passages 18 and 19 in the section 6. The spring fingers 16 and 17 have outwardly extending bases or feet 20 provided with laterally disposed lugs or ears 21 fitted in recesses or seats 22 in the section 6 near the lower ends of the passages 18 and 19, the lugs or ears 21 being firmly held in the recesses or seats 22 by the section 7; in other words the bases or feet 20 are clamped substantially between the sections of the base, thereby taking off some of the strain from the screws 23 and 24. The screw 23 extends through the flange 12 of the contact shell and is tapped into the foot or base of the spring 16, thus electrically connecting said finger or spring 16 with the contact shell 5. The screw 24 connects the extension 15 with the finger or spring 17, said screw 24 being tapped into the base or foot 20 of the finger or spring 17. The cap or section 2 is provided with similar fingers or springs 25 attached thereto in any desirable manner and adapted to be connected 110

with the wires of the cord 26. The separable cap or section 3 and its adjuncts are not uncommon and are not in themselves novel with me, for which reason they are not described further in detail.

What I claim is:

An attachment plug comprising an insulating base having main and auxiliary sections, a threaded contact shell surrounding the main section, having a flange at its bottom clamped between the sections of the base, contact fingers in the base having outwardly extending feet provided with later-

ally disposed lugs also clamped between said sections, the main section being chambered to receive said contact fingers, and an end contact electrically connected with one of said fingers, the other finger being electrically connected with said shell. 15

In testimony whereof I affix my signature 20 in presence of two witnesses.

JOHANN G. PETERSON.
